COSMETIC DISPLAY SELF-SERVICE COUNTER

Douglas J. Alippe, Tuxedo, and Frank A. Desisto,
Yonkers, N.Y., assignors to J. C. Penney Company,
Inc., New York, N.Y.

Original design application Sept. 24, 1970, Ser. No.
25,564. Divided and this application, Feb. 9, 1972,
Ser. No. 225,027

Term of patent 14 years

Int. Cl. D6—04

U.S. Cl. D6—149

FIG. 1

FIG. 2

FIG. 3

FIG. 1 is a perspective view of a cosmetic display self-service counter showing our new design;

FIG. 2 is a top plan view thereof; and

FIG. 3 is a front elevation view thereof.

The vertical faces of the counter not shown are like the face at the right forefront of FIG. 1.

This is a division of design application Ser. No. D. 25,564, filed Sept. 24, 1970.

We claim:

The ornamental design for a cosmetic display self-service counter, substantially as shown and described.
